[57] CLAIM

The ornamental design for a brake pedal depressor tool, as shown and described.

DESCRIPTION

FIG. 1 is a front elevational view of a brake pedal depressor tool showing my new design;

FIG. 2 is a top plan view thereof;

FIG. 3 is a bottom plan view thereof;

FIG. 4 is a rear elevational view thereof;

FIG. 5 is a left elevational view thereof;

FIG. 6 is a right elevational view thereof; and

FIG. 7 is a second embodiment of FIG. 1 with the lever handle in an extended position.
